UNITED STATES PATENT OFFICE

2,549,238

HEATING SYSTEM AND APPARATUS

Karl L. Reinke, Oak Park, Ill.

Application October 15, 1945, Serial No. 622,262

9 Claims. (Cl. 237—68)

1

This invention relates particularly to a system for evenly distributing steam or other heating mediums so that even the remotest radiators may receive heat in timed relation and as soon as others closer to the source of heat supply.

An important object of the invention is to provide an air vent in conjunction with a retarder which permits air to be purged from a radiator or from a heating line only after the heating medium has reached a predetermined pressure.

A further object of the invention is to provide a retarder in conjunction with an air vent to balance the pressure and to build up pressure as desired in different radiators so that any radiator or a part of the system may receive heat before or after other radiators in that same part of the system.

A further object of the invention is to provide a heating system having a combined air vent and retarder in connection with separate radiators whereby they may be independently adjusted for receiving heat in timed relation to the remainder of the system.

Still a further object of the invention is to provide a combination of air vents and retarders in connection with the heating supply lines and in advance of the radiators of a portion of the system as well as in connection with the separate radiators of a system so that where a group of buildings are heated by one central plant, the radiators will allow the heating medium to be transmitted and utilized in the most distant buildings at the same time as it enters the nearest feeder lines.

A further object of the invention is to provide a system and apparatus in which a pressure may be built up in the entire main supply line before a heating medium enters the lateral feeders to increase the efficiency of the heating system by insuring the distribution of heat uniformly or as desired to all radiators.

Still a further object of the invention is to provide a new and improved retarding device for use separately or in combination with an air vent to insure that air is purged from a radiator only after a predetermined pressure has been built up in the air vent and retarder.

Other and further objects of the invention will appear in the specification and will be apparent from the accompanying drawings in which

Fig. 1 illustrates a fragment or portion of a heating system in which the retarder of the present invention is utilized and applied;

Fig. 2 is an enlarged view showing an air

2

valve, a retarder and a water returning trap as employed in connection with the system shown in Fig. 1;

Fig. 3 is a sectional view of a retarder in accordance with this invention having a weighted cone above the pressure disc;

Fig. 4 is a sectional view of a retarder in accordance with this invention having a weighted cone with a pressure disc above the cone;

Fig. 5 is a sectional view of a retarder having an adjustable pressure spring for holding it in place;

Fig. 6 is a sectional view of a retarder comprising a variably weighted disc without any returning spring;

Fig. 7 is a sectional view of a retarding device with a weighted disc adapted to be controlled by an electro-responsive device such as a magnetic coil;

Fig. 8 is a sectional view of a combined air vent and retarder in accordance with this invention in lowered position;

Fig. 9 is a sectional view of the structure of Fig. 8 in heated and raised position;

Fig. 10 is a sectional view of a common type of air vent valve;

Fig. 11 shows an air vent valve with a protected discharge opening; and

Fig. 12 shows an air vent valve of the type shown in Fig. 11 with the protector fitting removed and a ball type of retarder in accordance with this invention applied directly to the threaded stem at the top of the air vent.

Where a single or central furnace is used for heating a large building such as an apartment building, which has a large number of radiators located at different distances from the central heating plant, and where even the radiators of the same apartment require a different amount of heat for properly supplying the different rooms which they serve, it is extremely difficult to utilize the present air vents for meeting the different conditions and for supplying heat in timed relation as desired. By determining the pressure in the system at various points from the furnace, a retarder may be installed in which the pressure required to operate the retarder may be varied depending upon the heat demanded.

By combining an air vent with a retarder, a pressure may be built up in all of the radiators which permits the air to be purged or released from a radiator only after the steam or heating medium has reached a predetermined pressure. By varying the pressure of the different radiators in any one apartment, for

example, the bathroom radiators may be adjusted to receive heat first, the living room radiators to receive heat next, and the dining room, kitchen and bedroom radiators to receive heat in succession, or at the same time, or in any timed sequence as desired.

In carrying out and operating this system, an assembly and arrangement as shown in part by Fig. 1 may be employed in which a boiler or furnace 15 has a main heating pipe line 16 and a return or water line 17.

The main line may extend for a long distance and may be provided with successive reductions 18, 19 and the like. From each portion of the main line a number of separate heating lines 20 may extend and be suitably connected to radiators 21 and 22 located at various distances from the main heater. Various pipe line extensions 23 and 24 may extend to radiators 25 and 26 respectively at the same or different elevations with respect to each other, to the other radiators and to the main heater itself. At the end or between the ends of each main heating pipe line or the extreme end of the system an air vent device 27 may be provided to insure that the main feeder line will receive heat to the furthest extremity thereof before the heat is supplied to any of the individual radiators of the system. A similar air vent 28 may be applied to each separate heating line 20 to insure that heat will be delivered to that portion of the system in advance of a retarder 29 which controls the supply of heat to that portion of the system.

This retarder may consist of a sealing disc 30 carried by an arm 31 mounted on a pivot 32 at the top with a weight 33 attached to the lower end of the arm and at the side opposite the disc tending to hold the disc in closed relation against one end of a pipe of the separate heating line 20.

It is also desirable to provide a water trap 34 connected to the main pipe line and to the sectional pipe lines to receive water of condensation therefrom by means of a pipe 35 through an inlet 36 and to discharge it from the outlet 37 into the water return pipe 17. Mounted in this trap is a float 38 carried by a lever arm 39 for closing a valve 40 in the outlet 37 when an accumulation of water or liquid in the trap falls to a predetermined limit.

For any portion of the pressure supply line these parts are preferably mounted in succession, first the air vent 28, then the retarder 29 and then the water trap 34 to insure that the float return will not interfere with the proper operation of the air valve and the retarder.

One end of each radiator is connected to the heat supply line at the bottom of the radiator and the air vent or relief is connected to the other end of the radiator at the top thereof. In the ordinary installation the air vent may comprise a casing 41 as shown in Fig. 10 having a hollow threaded extension 42 at the bottom, and a discharge opening 43 at the top normally open when the radiator is cold and closed when the air valve is sufficiently warm. In the casing is a valve 44 to close the opening 43, the valve being carried by a stem 45 at the top of a closed hollow expansion member 46 having an expandable bottom 47 which rests upon a partition 48 in such a manner that when the expansion member 46 is heated sufficiently the bottom 47 will bulge outwardly causing the member to rise, carrying with it the stem 45 and the valve 44 closing the air discharge opening 43.

This type of air vent valve may be modified by

providing a threaded stem 49 as in Fig. 11 for the discharge outlet 50 with a fitting 51 normally protecting the discharge opening 50. By removing the fitting 51, a retarder of a type contemplated by this invention may be applied thereto which may be in one of the forms shown by Figs. 3 to 7 inclusive, or it may be a fitting 52 as shown in Fig. 12. This retarder comprises a ball 53 mounted in a retaining cage 54 having a valve opening 55 at the bottom closed by the ball 53 in its downward position and because of the weight of the ball, requiring a certain pressure to raise the ball from the opening 55 to permit the passage of air therethrough. The cage has openings 56 at the top thereof which permit the discharge of air when the ball is raised from its seat 55.

Instead of a ball type of retarder as shown in Fig. 12, a weighted retarder may be used as shown by Fig. 3 which comprises a casing 57, having a lower partition 58 with a central opening 59 to receive a valve stem 60 therethrough and with outer openings 61 normally covered by a valve disc 62 secured to the stem. Attached to the stem above the disc is a conical device 63 adapted to close a conical opening 64 in a cross partition 65 when sufficient pressure is applied to the casing and with a spring 66 surrounding the conical portion and bearing against it and the lower side of the partition 65 tending to hold the disc 62 in closed position on the lower partition 58. Above the partition 65 is a central guide 67 for receiving the upper end of the stem 60. An inlet pipe 68 is connected to the bottom of the casing, a discharge opening 69 is provided above the conical valve opening 64 in the side wall of the casing and a cover 70 closes the top of the casing.

In the retarders shown by Fig. 4, a casing 71 has an inlet pipe 72 at the bottom and a cover 73 with discharge openings 74 in the top. Extending transversely in the casing is a partition 75 having a central conical opening 76 and a plurality of surrounding openings 77 closed by a disc 78 on top of the partition. Suspended by the disc and connected to a central stem 79 thereof is a conical weight 80 adapted to close the opening 76 when it is sufficiently raised by pressure applied to the casing, the closing being opposed by a light spring 81 which bears at its upper end against the under-side of the partition and at its lower end against the conical wall of the weight.

The casing of Fig. 5 may be provided with a partition 82 having a retarding pressure opening 83 at one side thereof closed by a disc valve 84 mounted at one end of a spring holder 85 the other end of which is secured by a suitable fastening device 86 to the wall of the partition 82. The valve is held in place by a spring 87 surrounding a stem 88 which passes through the holder 85 and the partition 82 and is supported at the underside of the partition by a projection 89. At the upper end of the stem is a thumb screw 90 bearing against the upper end of the spring, the lower end of which bears against the holder 85 thereby tending to retain the valve 84 covering the discharge opening 83 until the pressure admitted to the casing is sufficient to overcome the pressure of the spring 87.

As shown in Fig. 7 a valve 91 having a stem 92 may be seated at the upper end of a sleeve 93 extending from a partition 94 in the casing 71, the sleeve providing space for receiving a magnetic winding or coil 95 which has conductors 96

extending therefrom to a suitable source of current supply and means, not shown, for controlling current to the winding. The valve 91 is retained in position by inner guides 97 and when the coil is energized, the disc is held seated against any pressure which enters the pipe 72, but if the pressure is sufficient and the coil is de-energized, the valve may be raised to permit a flow of fluid outwardly from the openings 74 of the casing.

In the form of the invention shown by Fig. 6, a casing 100 has a pipe 101 threaded into an inlet opening 102 and at the top is a cover 103 having an outwardly threaded hollow stem 104 which corresponds to the opening 102 so that a number of such casings can be connected one to another, the stem 104 of one extending into the threaded opening 102 of the other, thus connecting them in series. Extending transversely within the casing is a partition 105 having openings 106 surrounding a central opening 107 for receiving the stem 108 of a disc valve 109 on top of the partition and adapted to cover the openings 106. A number of discs 110 may be applied to the valve disc 109 and held thereon by fastening means 111, the additional discs acting as weights so that the opening of the valve 109 may be varied depending upon the weight supplied thereto. For example, the valve 109 may require pressure of one ounce to raise it and the addition of one disc 110 may require two ounces of pressure to raise the valve, likewise additional retarders may be connected in series to provide additional retarding effect. For heating systems already installed, retarders as shown more particularly by Figs. 3 to 7 and Fig. 12, may be employed, but if desired, the air valve and retarder may be combined in one device as shown more clearly by Figs. 8 and 9. In this form a casing 112 has an inlet 113 at the bottom and a cover 114 with discharge openings 115 at the top. In the casing is a hollow expandable member 116 having a deflectable bottom 117 which extends outwardly as shown in Fig. 9 when it becomes sufficiently heated. Extending downwardly from the bottom is a supporting stem 118 extending through a supporting guide 119 and having a collar 120 at a distance from the end of the stem. Extending upwardly from the top of the member 116 is a guide stem 121 having a lower conical projection 122 and an upper disc 123 with a lower conical projection 124. The stem 121 extends through a partition 125 having an upper conical opening 126 for receiving the upper cone 124 and a lower conical opening 127 for receiving the lower conical portion 122. With this construction the expandable member 116 is supported by the disc 123 in engagement with the top of the partition 125 when the expandable member is cold, the collar 120 at this time being positioned above its guiding partition 119 as shown more clearly in Fig. 8. When the pressure in the casing is sufficient to raise the valve disc 123, a flow is permitted through the casing from the inlet 113 through the discharge openings 115. This requires that a certain pressure be built up in the casing to permit the opening, but after a radiator has been vented in this manner and warm or hot air or other fluid is admitted in the casing, the expandable member will be extended so that the bottom 117 bulges outwardly as shown in Fig. 9 thereby moving the stem 118 downwardly until the collar 120 engages the partition 119 which will correspondingly raise the upper stem 121 so that the stem will first permit a free flow of air or other fluid

through the valve opening 126, 127 and then the lower conical portion 122 will be moved into engagement with its conical opening 127 thereby closing the retarder against any further passage of air or other fluid through the casing 112.

With this construction and apparatus embodied in a system as represented in part by Fig. 1, it is apparent that the separate radiators of an apartment may be regulated, for example, so that any radiator will receive heat before the other radiators, or if desired all the radiators of the apartment may receive heat at the same time.

Where a large building or a group of buildings are heated by one central plant, retarders may be installed in the individual heating lines to allow the heating medium to be transmitted to the most distant buildings at the same time as it would enter the nearest feeding lines. In this way a pressure could be built up in the entire main line before any heating medium would enter the lateral or subsidiary feeders. A retarder and system in accordance with this invention will work expressively well during weather varying from warm to medium when only short spurts of steam are required to heat the building, and also during the early morning warm-up period, when the supply pipes are cold or ordinarily filled with cold air. Under these conditions there is usually overheating near the boiler and underheating farther from the boiler. By adjusting the retarders at the ends of the steam lines to open under line pressure and to insure that steam is filling up the mains entirely to the ends thereof, the main supply line may be freed of air completely through air vents installed at the ends of the supply lines and therefore heated to the most distant point before any steam whatever is allowed to enter any radiator, including those nearest the boiler or furnace.

With this construction and system various other changes in the construction, combination and arrangement of the parts may be provided in a variety of ways without departing from the spirit and scope of the invention.

I claim:

1. In a heating system, a heater and heat supply pipes extending therefrom, a plurality of radiators spaced at different distances and different elevations with respect to the heater, fluid supply pipes connected to the radiators, air vent and pressure retarding devices in the pipes in advance of the radiators, air vent devices connected to the upper portion of the individual radiators, each air vent device for the individual radiators comprising a casing having a hollow expansion member movable therein by the application of heat, a partition forming an air venting opening, a weighted retarder on top of the partition for closing the opening and connected by a reduced stem to the expansion member, a valve spaced from the retarder on the stem below the partition for closing the opening when the expansion member is moved by the heat and air venting devices in the heat supply pipes at distances from the heater to insure that heat will be delivered to the extremities of the supply pipes before heat is supplied to the individual radiators of the system.

2. In a heating system, a main heater and main heat supply pipes extending therefrom, a plurality of radiators connected to the supply pipes at different distances and elevations from the heater, each radiator having a casing with a hollow expansion member movable therein by the application of heat, a partition forming an air

venting opening, a weighted retarder on top of the partition for closing the opening and connected by a reduced stem to the expansion member, a valve spaced from the retarder on the stem below the partition for closing the opening when the expansion member is moved by the heat and air venting means connected to the heat supply pipes at the remote extremity of the main heating line to insure that the main heating line will receive heat to the extremity thereof in timed relation to the supply of heat to the individual radiators of the system.

3. In a heating system, a heater and a main heating pipe line extending therefrom, a plurality of radiators connected to the pipe line at different distances from the heater, fluid pressure venting and weighted retarding means connected to the upper portion of each of the radiators having a casing with a hollow expansion member movable therein by the application of heat, a partition forming an air venting opening, a weighted retarder on top of the partition for closing the opening and connected by a reduced stem to the expansion member, a valve spaced from the retarder on the stem below the partition for closing the opening when the expansion member is moved by the heat so that radiators having similarly weighted retarders will receive heat from the pipe line in accordance with their distance from the heater, and air venting means at the remote extremity of the pipe line to insure that all of the main heating pipe line will receive heat to the extremity thereof before the weighted retarders will admit heat to the radiators.

4. In a heating system, a source of heat supply and a pipe line extending therefrom, a plurality of radiators in different sets connected to the pipe line at different distances from the source of heat supply, the different sets of radiators having a separate supply pipe connected to the main pipe line, air vent means at the remote extremity of the main pipe line, an air vent and fluid pressure retarding means connected to the supply pipe for a particular set of radiators, and air venting and weighted pressure retarding means connected to the upper portion of each radiator, each radiator having a casing with a hollow expansion member movable therein by the application of heat, a partition forming an air venting opening, a weighted retarder on top of the partition for closing the opening and connected by a reduced stem to the expansion member, a valve spaced from the retarder on the stem below the partition for closing the opening when the expansion member is moved by the heat the weights of the retarders being varied for radiators in each individual set so that the different rooms of any particular set will receive heat in a predetermined sequence.

5. In a heating system, a source of heat supply and a heating pipe line extending therefrom, a plurality of radiators connected to the pipe line at different distances from the source of heat supply, air venting and weighted pressure retarding means in the pipe line in advance of the radiators, air venting and weighted retarding means connected to the upper portion of each of the radiators, comprising a casing having a hollow expansion member movable therein by the application of heat, a partition forming an air venting opening, a weighted retarder on top of the partition for closing the opening and connected by a reduced stem to the expansion member, a valve spaced from the retarder on the stem

below the partition for closing the opening when the expansion member is moved by the heat the weights of the retarders being varied in different radiators to insure the supply of heat thereto in predetermined order, and water trapping means connected to the source of heat supply and to the main pipe line following the air venting and retarding means in advance of the radiators.

6. In a heating system, a source of heat supply, a radiator connected by a pipe line to the source of heat supply, means for regulating the timing of the supply of heat to the radiator with relation to the pressure of the heat supply, said means comprising an air venting and weighted pressure regulating device connected to the upper portion of the radiator, said device comprising a casing having a hollow expansion member movable therein by the application of heat, a partition forming an air venting opening, a weighted retarder on top of the partition for closing the opening and connected by a reduced stem to the expansion member, a valve spaced from the retarder on the stem below the partition for closing the opening when the expansion member is moved by the heat the weight of the pressure regulating device being variable to change the pressure at which the retarder will be opened by pressure within the radiator.

7. In a heating system, a source of heat supply, a pipe line and a plurality of radiators connected thereby to the heat supply, a combined air venting and fluid pressure retarding device for a radiator comprising a heat responsive expansion member with a valve thereon for controlling an air vent at the upper portion of the radiator, a weighted valve in combination with the expansion member to also close the air vent, the weighted valve having a reduced stem extending through the air vent and connected to the expansion member, a valve carried by the expansion member at the other side of the air vent for also closing it when the expansion member is expanded, the weighted valve closing the air vent when the expansion member is not expanded to insure a predetermined pressure applied to the expansion member before the air vent is opened to the atmosphere.

8. In a heating system for radiators, a source of heat supply, a pipe line extending from the source of supply to the radiators, an air venting and retarding device comprising a casing applied to the upper venting opening of a radiator, the casing having a hollow expansion member movable therein by the application of heat, means forming an air venting opening, a weighted retarder closing the opening and connected by a reduced stem through the opening to the expansion member, and a valve spaced from the retarder and connected to the expansion member and the stem for closing the opening from the other side when the expansion member is moved by the heat, the arrangement being such that the weighted retarder will maintain the air vent closed until sufficient pressure is applied in the casing, whereupon the expansion member is moved before it is heated to open the valve and the expansion member being operated after it is heated to close the valve.

9. In a heating system, a source of heat supply, a pipe line and a plurality of radiators connected thereby to the heat supply, a weighted pressure retarder for each of the heating radiators comprising a weighted valve structure for connection to the discharge end of a radiator air vent valve, the weight of the retarder valve be-

ing changed for different predetermined pressures and the valve being normally closed but opened by pressure from within the radiator, and an air valve attached to the radiator comprising a casing with a partition with an air relief opening therein, a weighted valve at the top of the partition for closing the opening, an expansion member below the partition movable toward and from the partition by its expansion, a valve at the top of the expansion member, a stem connecting the valves at the top and below the partition for moving the valves to open one valve and to close the other in accordance with the movement of the expansion member to insure that the air valve of the radiator will remain closed for the discharge of air from the radiator until a predetermined pressure has been

built up in the radiator, in the air vent and in the retarder.

KARL L. REINKE.
